(57) **CLAIM**

The ornamental design for a portion of a display screen with a graphical user interface having a progress indicator, as shown and described.

DESCRIPTION

FIG. 1 is a front view of a first image of a portion of a display screen with a graphical user interface having a progress indicator.

FIG. 2 is a second image thereof.

FIG. 3 is a third image thereof.

FIG. 4 is a fourth image thereof.

FIG. 5 is a fifth image thereof.

FIG. 6 is a sixth image thereof.

FIG. 7 is a seventh image thereof.

FIG. 8 is an eighth image thereof.

FIG. 9 is a ninth image thereof.

FIG. 10 is a tenth image thereof.

FIG. 11 is an eleventh image thereof.

FIG. 12 is a twelfth image thereof.

FIG. 13 is a thirteenth image thereof.

FIG. 14 is a fourteenth image thereof.

FIG. 15 is a fifteenth image thereof.

FIG. 16 is a sixteenth image thereof; and,

FIG. 17 is a seventeenth image thereof.

The appearance of the transitional image sequentially transitions between the images shown in FIGS. 1, 2, 3, 4, 5, 6, 7, 8, 9, 10, 11, 12, 13, 14, 15, 16, and 17. The process or period in which one image transitions to another image forms no part of the claimed design. The broken lines, showing a portion of the display screen, are for the purpose of illustrating environment and form no part of the claimed design. The broken lines showing text and portions of the graphical user interface form no part of the claimed design. The greyscale filled elements represent a contrasting appearance from other portions of the design.
